INVENTOR

Davis Marinsky

UNITED STATES PATENT OFFICE.

DAVIS MARINSKY, OF NEW YORK, N. Y.

MEANS FOR CREASING THE LEGS OF TROUSERS.

979,780.

Specification of Letters Patent. Patented Dec. 27, 1910.

Application filed December 18, 1909. Serial No. 533,765.

To all whom it may concern:

Be it known that I, DAVIS MARINSKY, a citizen of the United States, and residing at New York, in the county of New York and State of New York, have invented certain new and useful Improvements in Means for Creasing the Legs of Trousers, of which the following is a specification, such as will enable those skilled in the art to which it applies to make and use the same.

This invention relates to means or devices for use in creasing the legs of trousers and it consists of a strip of fabric, which is secured within, centrally of and longitudinally of the front of the trouser legs, said strip being provided centrally and longitudinally with a bead over and around which the fronts of the trouser legs are folded and pressed.

The invention is fully disclosed in the following specification, of which the accompanying drawing forms a part, in which the separate parts of my improvement are designated by suitable reference characters in each of the views, and in which:—

Figure 1 is a front view of a pair of trousers, the legs of which are provided with my improved creasing device or devices, the front part of one of said legs being broken away; Fig. 2 a partial transverse section of the front of one of the trouser legs taken on the line $x-x$ of Fig. 1, and on an enlarged scale; Fig. 3 a view similar to Fig. 2, but showing a modification; Fig. 4 a view similar to Figs. 2 and 3 and showing another modification; Fig. 5 a front view of the creasing strip which I employ; Fig. 6 an end view of said strip; Fig. 7 a view similar to Fig. 5 but showing a modification; Fig. 8 an end of the strip shown in Fig. 7; Fig. 9 a view similar to Fig. 5 but showing another modification, and; Fig. 10 an end view of a strip shown in Fig. 9.

In the drawing forming part of this specification I have shown at a a pair of trousers, the legs a^2 of which are provided with my improved creasing strip b .

The creasing strip b , as shown in Figs. 1, 2, 5 and 6 is composed of a narrow strip of fabric, provided centrally of the front side with a longitudinal bead b^2 and said bead as shown in Figs. 2, 5 and 6 is formed by folding said strip centrally and longitudinally and stitching it parallel with the fold-

ed edge as shown at b^3 . In practice the front side of the strip b is gummed in any desired way, or a thin strip of gum material is placed between it and the trouser leg, and a hot iron is passed over said strip, and this operation secures the strip b to the trouser leg, as will be readily understood. The trouser leg is then folded longitudinally and centrally of the front thereof and around the bead b^2 , and is pressed in the usual manner to form the usual crease, and the bead b^2 retains the trouser leg in its creased form and a repressing thereof or a recreasing thereof is not necessary except at long intervals.

In Figs. 3, 7 and 8 I have shown another method of forming the bead b^2 , which consists in folding the strip b around a cord b^4 , which is arranged centrally and longitudinally thereof and stitching the folded strip inwardly of said cord, as shown at b^5 in Fig. 8. This operation forms the bead shown in Figs. 2, 5 and 6, and the bead will retain the trouser leg in a creased condition much longer than other means, or method of operation now in use.

In Figs. 4, 9 and 10 I have shown another method of forming the bead b^2 which consists in passing a cord b^6 centrally and longitudinally of, and back and forth through the strip b , or by stitching said cord through said strip as clearly shown in Fig. 9, after which the strip b is folded centrally and longitudinally as shown in Fig. 4 and the cord b^6 forms the bead b^2 .

In the construction shown in Figs. 3 and 4, and in Figs. 7 to 10 inclusive, the creasing strip b is secured to the trouser leg in the same manner as with the construction shown in Figs. 1 and 2 and the result will be the same.

My invention is not limited to the use of any particular material in forming the strip b , nor to any particular method of, or means for forming the longitudinal bead b^2 , all that is necessary, in this connection, being that the said strip be provided centrally and longitudinally with a bead around which the trouser legs are folded in the operation of pressing and creasing the same, and that said strip be secured in the trouser legs, in the manner shown and described.

Having fully described my invention, what

I claim as new, and desire to secure by Letters Patent, is;—

1. A pair of trouser legs, the front of which are provided on the inner sides thereof and longitudinally thereof with creasing strips, consisting of flexible material and having a cord secured thereto longitudinally thereof and forming a longitudinal bead.
2. A pair of trousers, the legs of which are provided on the inner sides thereof and longitudinally thereof with creasing strips consisting of fabric material, said creasing

strips having a central longitudinal bead on the outer side thereof over and around which the trouser legs are folded in the operation 15 of pressing and creasing the same.

In testimony that I claim the foregoing as my invention I have signed my name in presence of the subscribing witnesses this 17th day of December 1909.

DAVIS MARINSKY.
